Primary Examiner — Cathron C Brooks*(74) Attorney, Agent, or Firm* — Merchant & Gould P.C.(57) **CLAIM**

The ornamental design for an active seat with desk, as shown and described.

DESCRIPTION

FIG. 1 is a top perspective view of an active seat with desk; FIG. 2 is a bottom perspective view of the active seat with desk of FIG. 1;

FIG. 3 is a rear elevational view of the active seat with desk of FIG. 1;

FIG. 4 is a front elevational view of the active seat with desk of FIG. 1;

FIG. 5 is a first side elevational view of the active seat with desk of FIG. 1;

FIG. 6 is a second side elevational view of the active seat with desk of FIG. 1;

FIG. 7 is a top plan view of the active seat with desk of FIG. 1; and,

FIG. 8 is a bottom plan view of the active seat with desk of FIG. 1.

The broken lines in the drawings illustrate portions of the active seat with desk that form no part of the claim.
